Primary Examiner — John Windmuller
Assistant Examiner — John R Yeh

(57) **CLAIM**

The ornamental design for a sponge and steel wool pad, as shown and described.

DESCRIPTION

FIG. 1 is a front perspective view of my design for a sponge and steel wool pad;
FIG. 2 is a rear perspective view thereof;
FIG. 3 is a front elevation view thereof;
FIG. 4 is a rear elevation view thereof;
FIG. 5 is a left elevation view thereof;
FIG. 6 is a right elevation view thereof;
FIG. 7 is a top plan view thereof;
FIG. 8 is a bottom plan view being thereof;
FIG. 9 is a front perspective view of the sponge and steel wool pad in an alternate position; and,
FIG. 10 is a front perspective view of the sponge and steel wool pad in another alternate position.

1 Claim, 10 Drawing Sheets(56)
